CLAIM

The ornamental design for revolving plant basket hanger, as shown and described.

DESCRIPTION

FIG. 1 is a front perspective view of a revolving plant basket hanger, showing my new design, wherein the broken line showing of a flowerpot forms no part of the claimed design; FIG. 2 is an exploded front perspective view thereof, shown in an alternate position of use;

FIG. 3 is a top plan view thereof, shown at an enlarged scale; FIG. 4 is a bottom plan view thereof, shown at an enlarged scale;

FIG. 5 is an exploded top plan view thereof, shown at an enlarged scale; and

FIG. 6 is an exploded bottom plan view thereof, shown at an enlarged scale, wherein broken line matter is environmental and forms no part of the claimed design.

FIG. 7 is an exploded front perspective view of a second embodiment of a revolving plant basket hanger;

FIG. 8 is a top plan view thereof, shown at an enlarged scale; FIG. 9 is a bottom plan view thereof, shown at an enlarged scale;

FIG. 10 is an exploded top plan view thereof, shown at an enlarged scale, wherein broken line matter is environmental and forms no part of the claimed design; and

FIG. 11 is an exploded bottom plan view thereof, shown at an enlarged scale.

FIG. 12 is an exploded front perspective view of a third embodiment of a revolving plant basket hanger;

FIG. 13 is a top plan view thereof, shown at an enlarged scale; FIG. 14 is a bottom plan view thereof, shown at an enlarged scale;

FIG. 15 is an exploded top plan view thereof, shown at an enlarged scale, and

FIG. 16 is an exploded bottom plan view thereof, shown at an enlarged scale, wherein broken line matter is environmental and forms no part of the claimed design.

FIG. 17 is an exploded front perspective view of a fourth embodiment of a revolving plant basket hanger;

FIG. 18 is a top plan view thereof, shown at an enlarged scale;

FIG. 19 is a bottom plan view thereof, shown at an enlarged scale;

FIG. 20 is an exploded top plan view thereof, shown at an enlarged scale, wherein broken line matter is environmental and forms no part of the claimed design; and

FIG. 21 is an exploded bottom plan view thereof, shown at an enlarged scale.

FIG. 22 is an exploded front perspective view of a fifth embodiment of a revolving plant basket hanger;

FIG. 23 is a top plan view thereof, shown at an enlarged scale;

FIG. 24 is a bottom plan view thereof, shown at an enlarged scale;

FIG. 25 is an exploded top plan view thereof, shown at an enlarged scale, wherein broken line matter is environmental and forms no part of the claimed design; and

FIG. 26 is an exploded bottom plan view thereof, shown at an enlarged scale.

FIG. 27 is an exploded front perspective view of a sixth embodiment of a revolving plant basket hanger;

FIG. 28 is a top plan view thereof, shown at an enlarged scale;

FIG. 29 is a bottom plan view thereof, shown at an enlarged scale;

FIG. 30 is an exploded top plan view thereof, shown at an enlarged scale, wherein broken line matter is environmental and forms no part of the claimed design; and,
